UNITED STATES PATENT OFFICE.

CARL A. W. BRANDT, OF GREAT NECK, NEW YORK, ASSIGNOR TO THE SUPERHEATER COMPANY, OF NEW YORK, N. Y., A CORPORATION OF DELAWARE.

BOILER.

Application filed October 31, 1924. Serial No. 747,032.

My invention relates to water tube boilers and particularly to boilers of this class which are to be used with pressures of the order of a thousand pounds or more per square 5 inch. While of special utility in connection with such pressures its use is not restricted to them.

The object of my invention is to provide a boiler of the type spoken of which shall 10 be inexpensive to manufacture, and safe and economical to operate and maintain.

Two forms of my inventive idea are described in what follows and are illustrated in the accompanying sheets of drawings, 15 where Fig. 1 is a composite view, the right half being a front elevation of the boiler and the left half a section on the line 1—1 of Fig. 2 looking in the direction indicated by the arrows; Fig. 2 is a central sectional view 20 at right angles to Fig. 1; and Fig. 3 shows a modification, the left half being a front elevation and the right half a vertical central section.

I shall first describe fully the form of my 25 invention shown in Figs. 1 and 2.

The fuel for heating the boiler according to this form is burned on grates 1—1 in the lower part of the space enclosed by housing 2. Above the grates is the furnace 3 and the 30 combustion space 4. It will be understood from what follows that if desired the furnace may be designed for burning other fuels, such as pulverized coal, oil, or gas, in which case the grates will be replaced 35 by suitable burners, the heating surface of the boiler is located at each side of the combustion space and is so arranged that said space has the shape of an A or an inverted V, being widest at the bottom and narrowing 40 progressively to a point at the top.

The heating surface of the boiler comprises straight tubes whose ends are secured in juxtaposed headers. These headers are arranged adjacent to the left and right walls 45 of the boiler setting, as viewed in Fig. 2, or front and back walls as seen in Fig. 1. Each header is rectangular in cross-section and is made up in one or more sections as required, the headers connected by the tubes 50 nearest the fire, for example, comprising three sections. Three such sections are shown at *a*, *b*, and *c*, respectively, at the left half of Fig. 1. It will be understood that the parts of the right half of Fig. 1, are 55 symmetrical with those shown in the left

half. The header next in order, going outward, also has three sections,—*d*, *e*, *f*, Fig. 1. The same is true of the fifth header. The third and fourth headers have each one long upper section, *u*, and *v*, respectively, 60 and a short lower section, *w* and *x*, respectively. The sixth and seventh headers have two sections each.

In each case, the several sections making up a header are interconnected by means of 65 nipples, as at 5—5.

The headers respectively opposite those shown in Fig. 1, i. e. those at the forward ends of the water tubes as seen in that figure, are arranged in generally corresponding 70 positions but somewhat lower. This will be clear from an inspection of Fig. 2. The water tubes 6—6 as a result, have an upward slope from one set of headers to the other set. The purpose in sloping the tubes is to 75 facilitate the water circulation through them and to permit an easier escape for the steam formed in the tubes. The headers at the left (Fig. 2) act as down-comers, those at the right having an upward flow of water 80 through them.

The water tubes connecting the headers *a*, *b*, and *c*, with the opposite headers are exposed not only to convection of the gases passing over them, but also to the intense 85 radiant heat of the furnace. It is therefore imperative that they should have an adequate and certain supply of water circulating through them. Similarly, the mixture of steam and water which it is necessary to 90 take off at the opposite ends of these tubes is large. It is for this reason that additional or supplementary circulating headers are provided. These are shown at *g*, *h*, *i*, *g'*, *h'*, and *i'*. The sections *g*, *h*, and *i* are nipped 95 together as shown, and near their upper ends, at *k* and *m*, the sections *g* and *h* are nipped to *a* and *b*; while near their lower ends, at *p*, *q*, and *r* the sections *g'*, *h'*, and *i'* are nipped to the sections opposite *a*, *b*, and *c*. 100 The sections *g* and *g'* have sections *j* and *j'* nipped to them, these two sections *j* and *j'* lying adjacent and parallel to the setting wall and being connected with the water tubes 7. It will be understood that the 105 right half of the boiler is correspondingly equipped with such supplementary circulation headers.

The upper part of the space between the second and fifth rows of tubes is occupied 110

by the heating surface of a superheater. The form of this apparatus shown in the drawing is one I prefer, but my invention is not limited to this form nor to this precise 5 location. For illustrative purposes the superheater is shown as composed of two headers, 8 and 9, and a series of tubular superheating elements or units 10, 10, whose ends are connected to the headers. The pipe 10 9^a connects the steam drum 14 to the superheater inlet header 9, and 8^a shows the outlet for the superheated steam.

From the top ends of the uppermost header sections, tubes 11—11 and 12—12 15 extend, the former connected to a cross-box 13, and the latter to the drum 14. The cross-box 13 is connected to the drum 14 by means of a set of pipes 15.

It will again be understood that the superheater and the pipes 11, 12 and 15 have their 20 counterparts in the other half of the boiler.

In addition to the sectional headers and the tubes above mentioned there are further tubes and headers located more remotely 25 from the furnace, and constituting an economizer. Some of these headers are seen at A—A, and tubes connecting those shown to corresponding ones opposite them are seen at 16—16. It will be understood that these 30 economizer headers and tubes are so connected up with each other and with the water supply to the boiler that the water flows through them on its way to the boiler. The particular order in which the flow of water 35 occurs through the economizer is obviously immaterial and no detailed showing seems called for.

Stack connections are shown at 17 and 18.

40 The top of the boiler is covered by a partition 19, resting on the uppermost boiler and economizer tubes.

The action of the boiler is as follows. The fuel burning on grates 1 and in combustion 45 space 4 generates hot gases which travel toward stack connections 17—18, sweeping over the boiler, superheater, and economizer surfaces. From the form and disposition of the parts a natural contraction of the area 50 of the gas path occurs about proportional to the contraction which the gases experience as they are cooled by the heat absorbing surfaces.

The water flows downward through the 55 headers shown at the left in Fig. 2, toward the right through the water tubes 6, upward through the headers at the right and the tubes 11 into box 13, through circulating pipes 15 to the drum 14 and thence through 60 tubes 12 back to the headers at the left. The steam generated is carried by pipe 9^a to the superheater by which it is delivered in a superheated state to the outlet 8^a to be carried to the point of consumption.

65 The principal advantages of my boiler

will be readily seen by those skilled in this art. Among these advantages the following may be pointed out:

Throughout the boiler only straight tubes are used. Large drums, which are very expensive for high pressures, are avoided entirely. A comparatively large proportion of the boiler evaporating surface is exposed to the radiant heat of the furnace. The shape and arrangement of the tube heating surface are such that a large combustion space is provided without increasing the size of the boiler or the cubic contents of the setting. The water tube surface is extended downward so as to protect the refractory 70 furnace walls whose maintenance under modern boiler operation is very expensive. The headers to which the water tubes are secured are sectional and can be made of forged steel, rolled steel, or cast steel. The decrease in the gas area about proportional to the decrease in the specific gas volume is accomplished without resort to any baffling, which is always expensive to install and maintain. The fact that there are no reversals in the gas flow cuts down the draft losses. The superheater is arranged close enough to the furnace to furnish the high 75 degree of superheat which modern engineering demands, and yet is sufficiently protected against any excessive radiant and other heat by the interposition of water-cooled surfaces.

The tubes are so arranged that with respect to the direction of gas flow they are 80 staggered, and this is feasible in my boiler without the necessity of complicating the 85 form of the headers.

In the form of my boiler shown in Fig. 3, it will be noted at the outset that, while the general disposition of the furnace and boiler surfaces is like that in the form first described, the headers to which the boiler tubes are connected are here placed in a 90 vertical position. Those at the farther side (as viewed in the figure) are lower than the ones at the front so that the tubes connecting the two sets have the slope required for circulation. The headers increase progressively in length as we go from the center of the boiler outward, and they are made sectional for convenience, these sections being 95 as many in number as required for purposes of manufacture or as thought desirable. A space is left for the superheater 10^a, the 100 superheater elements lying generally parallel to the inclined sides of the combustion space and being separated from it by a limited 105 number of the water tubes.

No auxiliary means are shown in this modification for insuring sufficient water circulation, but such means may be provided if desired.

At the side of the boiler toward one as one views Fig. 3, the brick wall is shown pro-

tected by a water screen, the pipes 30 of which are connected at their upper ends to the boiler headers, and at their lower ends to the screen header 31. This header 31 is in 5 communication with the water space of the drum 14^a through the pipe 32.

A similar water screen may, if desired, be used to protect the farther wall.

A common blow-off 33 serves to blow out 10 impurities from the headers, to which it is connected by the pipes 34.

The operation of this form is very similar to that of the form first described, and does not appear to call for further statement.

15 What I claim is:

1. In a boiler of the class described the combination of a boiler setting, a furnace in the lower part of the setting, substantially horizontal boiler tubes extending across the 20 boiler space and arranged in two unbaffled substantially triangular groups with the points of the triangles down defining an inverted V-shaped combustion space immediately above the furnace with said boiler tube groups adjacent to the space, headers at opposite ends of the tubes to which the tubes are secured, the headers at one end being in a higher position than those at the other end, whereby the tubes have a slight 25 upward slope, a drum above the lower set of headers, a box above the higher set of headers, and tubes connecting the lower headers to the drum, the drum to the box, and the box to the upper headers, and a connection 30 to the stack from each of the upper outer corners of the triangular spaces. 35

2. In a boiler of the class described, the combination of a boiler setting, a furnace in the lower part of the setting, substantially horizontal boiler tubes extending across the 40 boiler space and arranged in two unbaffled triangular groups with the points of the triangles down defining an inverted V-shaped combustion space immediately above the furnace with said boiler tube groups adjacent to the space, a free space being left within 45 each tube group parallel to the side of the triangle facing the combustion space and separated from it by one or more rows of water tubes, headers at opposite ends of the tubes to which the tubes are secured, the headers at one end being in a higher position than those at the other end, whereby the tubes have a slight upward slope, blow off pipes adjacent to the lower ends of 50 the headers and connected to them, a drum above the lower set of headers, a box above the higher set, tubes connecting the lower headers to the drum, the drum to the box, and the box to the upper headers, a connection 55 to the stack from each of the upper outer corners of the triangular spaces, additional substantially horizontal water tubes below the points of the triangles and adjacent to the walls to form water-screens, end 60 headers to which these tubes are connected, and superheaters in said free spaces. 65
